(57) **CLAIM**

The ornamental design for a hanger support, as shown and described.

DESCRIPTION

FIG. 1 is a front perspective view of the hanger support.

FIG. 2 is a top plan view of FIG. 1.

FIG. 3 is a bottom plan view of FIG. 1.

FIG. 4 is a right side elevation view of FIG. 1.

FIG. 5 is a left side elevation view of FIG. 1.

FIG. 6 is a front elevation view of FIG. 1; and,

FIG. 7 is a rear elevation view of FIG. 1.

The shade lines adjacent to the broken lines define the boundary of the claimed design. Other broken lines indicate disclaimed portions of the design. None of the broken lines form part of the claimed design.
